UNITED STATES PATENT OFFICE.

PEDRO J. CALVENTO, OF MANILA, PHILIPPINE ISLANDS.

PENCIL CASE.

Application filed August 6, 1921. Serial No. 490,423.

To all whom it may concern:

Be it known that I, PEDRO J. CALVENTO, of Manila, Philippine Islands, have invented certain new and useful Improvements in 5 Pencil Cases; and I do hereby declare the following to be a full, clear, and exact description of the invention, such as will enable others skilled in the art to which it app pertains to make and use the same.

10 The object of my invention is to provide a simple pencil case, the parts of which are so arranged as to insure a writing instrumentality of appropriate balance without regard to the length of the contained pencil, and a 15 further object is to include as a part of such case a sharpener attachment which combines

with its usual function that of forming a seat for the pointed end of the pencil and which may be displaced relatively to a complementary part of the casing to protect the exposed lead of the pencil when not in use.

20 In the drawings, Figure 1 is a view in side elevation and Figure 2 is a longitudinal sectional view of my improved pencil case.

25 Figure 3 is a detached view of the sharpener and guard attachment. Figure 4 shows the cap removed with the free edge of a roll of paper projecting through the slot thereof.

30 My improved pencil case is primarily designed to give a proper balance to the pencil notwithstanding the length of the latter, and I attain this and the further advantage of being able to consume a pencil almost in its entirety by providing a cylinder 1 screw

35 threaded on its exterior and having an opening 2 in its otherwise closed end 3 and within which cylinder a pencil 4 is designed to be received. At one end of the cylinder and in a screw threaded telescopic engagement there-

40 with is a sleeve 5 having at its outer end and detachably secured thereto a cone shaped member 6 which has an opening 7 at its apex and a longitudinal slot 8 in connection therewith. A cutting blade 9 projects partly

45 over the slot and intercepts the periphery of the cone, such blade forming a pencil sharpening means. On the exterior of the cone and approximately diametrically opposite the slotted portion thereof I provide a holder

50 for a rubber eraser. At the other end of the cylinder 1 is a cap 12. It is of cylindrical form with a screw threaded end 13 by which it is fastened to the cylinder 1. Within this cap I propose placing a small roll of

55 paper, indicated at A, which will serve for jotting down memoranda, the paper being

readily withdrawn from the roll through an opening 14 of the cap and torn by using one of the walls of the slot as a knife edge. The roll is readily introduced into the cap 60 through the outer end and a closure 15 is then screwed thereon. This closure has a tension block 16 attached to its inner face and between which and a transverse, centrally apertured wall 17, the paper roll is 65 held. Manifestly upon loosening the closure 15 the roll may freely revolve within the cap and upon tightening the closure the roll is prevented from movement. Conveniently secured to the cap is a clip 18 by which the 70 pencil may be retained in the pocket of the user.

Within the cylinder 1 is a headed follower 20. Its screw threaded shank 21 projects through the opening 3 and through the central aperture of the wall 17, a milled nut 22 on the shank 21 and located between the end of the cylinder and the wall of the cap is the means by which the position of the follower in the cylinder is controlled. As the 80 pencil becomes shorter this milled nut is turned to cause the follower to push the pencil down into engagement with the cone shaped member 6, the cap being removed to give access to the milled nut. The free end 85 of the shank may be tapered to form a screw driver edge 23, a tool being thus provided by which screws of the blade 9 may be manipulated in removing and replacing the blade or in otherwise adjusting it. 90

The threaded engagement between the sleeve and cylinder permits movement of the sleeve to lengthen the pencil case and thus form a protection for the exposed lead when the pencil is not in use, telescoping 95 movement of the sleeve on the cylinder readily bringing the point into operative position through the opening 7.

I claim as my invention:

In a pencil case, a cylinder having an 100 opening in one end and also having a sleeve at one end and a cap at the other, each in screw threaded engagement with the cylinder, and said cap having a transverse apertured wall, said cylinder having a headed 105 pencil follower therein provided with a screw threaded shank which projects into said cap through the opening in said cylinder, a nut on said shank fitted between the end of said cylinder and the transverse wall 110 of said cap for moving said follower relatively to said cylinder to maintain the pencil

in writing position, said sleeve having a cone shaped member detachably secured thereto at one end and having an opening at its apex and a longitudinal slot in communication therewith, and a cutting blade projecting partly over said slot and intercepting the peripheral line of the cone, and said cap

forming a receiver for a roll of paper, the cap having a longitudinal slot through which the paper may be withdrawn.

10

In testimony whereof I have signed this specification.

PEDRO CALVENTO.
